UNITED STATES PATENT OFFICE.

HARRY T. ANDERSON, OF AVALON, PENNSYLVANIA, ASSIGNOR TO STANDARD STEEL CAR COMPANY, OF PITTSBURG, PENNSYLVANIA, A CORPORATION OF PENNSYLVANIA.

BRAKE-BEAM.

SPECIFICATION forming part of Letters Patent No. 752,277, dated February 16, 1904.

Application filed June 10, 1903. Serial No. 160,884. (No model.)

To all whom it may concern:

Be it known that I, HARRY T. ANDERSON, a resident of Avalon, in the county of Allegheny and State of Pennsylvania, have invented a new and useful Improvement in Brake-Beams; and I do hereby declare the following to be a full, clear, and exact description thereof.

My invention relates to brake-beams for railway-cars; and its object is to provide a device of this character which is simple and cheap to manufacture and which is very strong and yet light.

In the accompanying drawings, Figure 1 is a plan view of my brake-beam. Fig. 2 is an edge view of the same. Fig. 3 is an end view thereof. Fig. 4 is a transverse section on the line 4 4, Fig. 1; and Fig. 5 is a similar section on the line 5 5, Fig. 1.

The brake-beam is composed of two channel-shaped members 1, which are similar in construction and which preferably are formed of pressed plate metal. These members are placed, preferably, back to back—that is, with their webs toward each other and in contact—and are secured by means of rivets 3, passing through their webs. Preferably these members are of varying width, as shown, tapering from their middle toward their ends, and a portion at the extreme ends, as at 5, is straight or provided with parallel edges. The tapering effect, as shown in the drawings, is secured by having the back edge straight and the forward end tapering in both directions from the middle toward the ends; but obviously both edges of the beam might be made tapering, or the front edge might be straight and the rear edge alone tapering. The flanges 6 of these channel members also preferably taper from the middle toward the ends, as shown in Fig. 4. By this construction the beam is given not only the maximum lateral strength, but also the maximum strength to withstand vertical forces and with a minimum amount of weight of metal. For lightness the webs are cut out, as at 7, to remove superfluous metal, and the beam, in effect, is a truss.

At the ends the channel members are spread apart, as indicated at 8, and the brake-shoe

heads 9 are provided with projections 10, having parallel top and bottom walls, which fit in between the ends of the channel members and are secured therebetween by rivets or bolts 12, passing through the webs of the channel members and through suitable holes in the projections 10. At the center of the brake-beam the members 1 are spread apart or provided with the embossments 13, so as to form a space for receiving the projection 14 of the brake-lever fulcrum 15, which also is secured in place by means of rivets or bolts 16, passing through the webs of the channel members and holes in the projection 14. By the arrangement shown the brake-shoe heads and brake-lever fulcrum can be secured to the beam by very simple connections.

The brake-beam is simple of manufacture, as the two channel members being exact duplicates of each other can be struck up in dies, and the castings for the brake-shoe heads and brake-lever fulcrum are of simple form, and all parts can be readily and easily attached together by merely driving rivets straight through the webs of the channel members and through the projections of the castings. The finished beam is very light and possesses a high degree of strength. It can be made of any desired strength by merely varying the width of the webs or of the flanges, or both, of the channel members.

What I claim as my invention, and desire to secure by Letters Patent, is—

1. A brake-beam composed of two channel-shaped members placed back to back with their webs in contact, means for securing said members together, and a brake-lever fulcrum and brake-shoe heads secured to said members.

2. A brake-beam composed of two channel-shaped members of varying width placed back to back with their webs in contact and secured together, and a brake-lever fulcrum and brake-shoe heads secured to said members.

3. A brake-beam composed of two channel-shaped members having one edge straight and the other edge tapered from the middle toward both ends, said members being placed back to back with their webs in contact, means for se-

curing said members together, and a brake-lever fulcrum and brake-shoe heads secured to said members.

4. A brake-beam composed of two channel-shaped members of varying width having portions of their webs cut away, said members being placed back to back with their webs in contact, means for securing said members together, and a brake-lever fulcrum and brake-shoe heads secured to said members.

5. A brake-beam composed of two channel-shaped members provided with flanges of varying depth, and means for securing said members together.

6. A brake-beam composed of two channel-shaped members of varying width and provided with flanges of varying depth, said members being placed back to back, and means for securing the same together.

7. A brake-beam composed of two channel-shaped members secured together and having their ends separated or spread apart, and brake-shoe heads secured between the ends of said members.

8. A brake-beam composed of two channel-shaped members placed back to back, brake-shoe heads provided with parallel-faced projections placed between said members, and rivets or the like extending through said channel-shaped members and openings in the brake-shoe heads.

9. A brake-beam composed of two channel-shaped members placed back to back and spread apart at their middle portions, and a brake-lever fulcrum having a projection se-

cured between said members at the spread-apart portions.

10. A brake-beam composed of two channel-shaped members placed back to back, a brake-lever fulcrum provided with a projection having parallel faces and inserted between the channel-shaped members, and rivets or the like passing through the webs of said channel-shaped members and openings in the brake-lever fulcrum. 40

11. A brake-beam composed of two channel-shaped members placed with their backs toward each other, brake-shoe heads and a brake-lever fulcrum provided with projections having parallel faces, said projections being placed 50 between said channel-shaped members, and rivets or the like passing through the webs of said channel-shaped members and through openings in said projections.

12. A brake-beam composed of two channel-shaped members placed back to back, said members being spread apart at their ends and also at their middle portions, brake-shoe heads and a lever-fulcrum provided with projections having parallel faces and inserted between the 60 spread-apart portions of said members, and rivets or the like passing through the webs of said members and openings in said projections.

In testimony whereof I, the said HARRY T. ANDERSON, have hereunto set my hand.

HARRY T. ANDERSON.
